(57) **CLAIM**

The ornamental design for a desk mount for racing shifter simulator as shown and described.

DESCRIPTION

FIG. 1 is a top, front, left side perspective view of a desk mount for racing shifter simulator, showing my new design; FIG. 2 is a bottom, rear, right side perspective view thereof; FIG. 3 is a front elevational view thereof; FIG. 4 is a rear elevational view thereof; FIG. 5 is a right side elevational view thereof; FIG. 6 is a left side elevational view thereof; FIG. 7 is a top plan view thereof; FIG. 8 is a bottom plan view thereof; FIG. 9 is an enlarged view of portion 9 in FIG. 2; and, FIG. 10 is an enlarged view of portion 10 in FIG. 2. The evenly dashed broken lines illustrate portions of the desk mount for racing shifter simulator and form no part of the claimed design. The unevenly dashed broken lines define the boundaries of enlarged views and form no part of the claimed design.
